ABSTRACT OF THE DISCLOSURE

A device is provided for use with a helical element comprising means which selectively effect contact engagement with turns of the helical element and which withhold contact engagement during adjustment relative to the helical element.

This invention relates to devices having a helical element and an adjustable contactor therefor, and more particularly to such devices as radiation, inductance and resistance coils having means for selectively effecting contact engagement and for withholding contact engagement of the contactor during adjustment relative to turns of the helical element.

Heretofore contact devices have been proposed in which the turns of a helical element serve as threads to advance the contactor along the successive turns until the selected turn is in contact. Such known devices have incorporated means designed to insure continuous, positive contact during the traverse of the element because in every helical element there is some departure in the turns from a true helix. Accordingly, the contacting device must provide for such deviations and maintain contact at all times. As applied to an electrical conductor of a radiation, inductance or resistance coil this would be important from the standpoint of preventing undue heating and galling or wear of the conductor and contactor during timing. If a poor electrical contact is present, arcing and burning effects may arise which would seriously damage or abrade the conductor turns or the contactor and thereby render difficult or prevent subsequent selective adjustment or contactor traversal of the turns. In the past it has been proposed to bias rolling or sliding contactors outwardly against the inner surface of the turns to insure good contact and also to provide for irregularities in the curvature of the turns. Yet, with fatigue of the contactor metal, or occasionally recurring relaxation of the biasing means, uneven contacts will occur. In electrical applications this causes undue heating and results in the aforementioned arcing and abrading. Especially is this so where high currents are involved.

It is an object of the present invention, to provide a contact device, for use with a helical element, having means for selectively effecting contact engagement with turns of the helical element and for withholding contact engagement during adjustment relative to the helical element.

It is the further object of the present invention to provide a contact device with means which effect a smooth adjustment of the device along the length of a helical element via the turns thereof and selectively makes and breaks contact with helical turns as may be desired.

A feature of the invention is the use of camming means to coact with slidable contactors of the contact device disposed centrally of the helical turns of the element to make and break contact engagement with any selected turn.

The above mentioned and other features and objects of this invention will become more apparent by reference to the following description taken in conjunction with the accompanying drawings, in which:

FIG. 1 is a cross-sectional view of one embodiment of the invention;

2

FIG. 2 is an interior plan view of the contact device taken along line 2—2 of FIG. 1.

FIGS. 2A, 2B, and 2C illustrate different embodiments of contactors usable with the contact device of FIG. 2;

FIG. 3 is a cross-sectional view of another embodiment of the invention showing a modified arrangement for actuation of contactors;

FIG. 4 is an interior plan view of a contact device taken along line 4—4 of FIG. 3;

FIG. 5 is a cross-sectional view of the contact device of FIG. 4 taken along line 5—5;

FIG. 6 is a cross-sectional view of another embodiment of the invention showing another modification of the arrangement for actuation of the contactors;

FIG. 7 is an interior plan view of an inertially actuated contact device used in the embodiment of FIG. 4; and

FIG. 8 is a view of the contact device of FIG. 7 in a dynamic position showing the inertial lag of the device with respect to the camshaft.

Referring to the drawings, FIGURE 1 represents the helical element 1 having a plurality of turns 2 with an internal contact device 3. The contact device 3, of plastic or other non-conductive material, slides along drive rods 4 and a camshaft 5 substantially octagonal in cross-section, when traversing the length of the element 1. The rods 4 are mounted in a hub 6 in which an actuator shaft 7, slidably joined to one end of the camshaft, is centrally located. Rigidly fixed to the hub 6 is a spur gear 8 which meshes with gear 9. The actuator shaft 7 is slidably mounted in the hub 6, and an extended, smaller, hexagonal extension thereof 7' protrudes, slidably, into a hexagonal hollow 5' of camshaft 5. Between an internal shoulder 7" of the hub 6 and an external shoulder 7''' of the actuator shaft 7 is positioned a spring 10. Spring 10 urges the actuator shaft 7 away from the hub 6 and against the end of camshaft 5. The actuator shaft 7 has a dog-leg slot 11 in one side where it is coaxial with the hub 6. A dowel pin 12, extending from the hub 6 in which it is secured, extends through slot 11. Thus, actuator shaft 7, and the hexagonal extension 7' extending therefrom, can slide within hub 6, along the axis thereof, pin 12 and slot 11 slidably interacting to orient and limit the total axial and rotary displacements of actuator shaft 7. The end of the actuator shaft 7 opposite the camshaft 5 houses radial bearings 13. Mounted within these bearings is a short shaft 14. Bearing block 15 receives one end of shaft 14, and both are secured together by pin 54. To bearing block 15 one end of a lever 16 is slidably pinned by dowel pin 17. The other end of lever 16 is slidably joined to the rotary means 18 via dowel pin 19. Lever 16 is pivotally mounted in the center at point 20. Drive means 21 and braking means 22 provide input power and control to the power train of gears 8 and 9. End plate 23 receives and secures the ends of drive rods 4. End cap 24 and plate 23 provide bearing apertures 25, in the center of each, in which camshaft 5 can freely rotate. Base cap 26 provides a bearing aperture 27 in which hub 6 can rotate freely. Covering 28, in which turns 2 are disposed, provides a non-metallic cylinder which, with caps 24 and 26, protects the turns from adverse environments and permits RF radiation. Clamp 29 and wire lead 30 provide a coil connection for electrical applications of the helical element 1. Snap ring 55 sits in an annular recess in actuator shaft 7, between bearings 13, and snap rings 56 sit in annular recesses on short shaft 14 at either ends thereof to secure the bearings 13. Snap rings 55 and 56 position the bearings 13 on shaft 14 and insure that, with an axial displacement of shaft 14, actuator shaft 7 will also be displaced therewith.

The contact device 3 is shown in greater detail in FIGURE 2 where an internal plan view thereof is presented. There a plurality of contactors 31 of electrically-conductive material is shown slidably mounted in radial slots

58 in the contact device. The contact device 3 also has an annular groove 59 formed in the outer edge to receive a circular spring 32. Spring 32 is nested in recesses 60 formed in one surface of the contactors 31; the ends 61 of the spring are parted but are constantly being urged toward tangency. This urging causes contactors 31 to rest against camshaft 5. The camshaft 5 is shown in abutting relationship to the contactors 31. The drive rods 4 are also shown in cross-section through the contact device.

FIGS. 2A, 2B, and 2C show the contactor 31, and alternate embodiments, contactors 31' and 31'', respectively, usable in the contact device 3. Contactor 31 has a pair of resilient, arcuate-ended fingers 45 and 45a secured to a body 46. The fingers are so formed at the ends thereof, and are sufficiently resilient, to part slightly and present a concave contacting face to turn 2 upon being urged thereagainst. Contactors 31' and 31'' have pre-formed concave faces at the ends 47 and 48 thereof and are resiliently mated to the bodies 49 and 50. Contactor 31' has a spring 51 which provides resilient structural mating between end 47 and body 49, and an electrically-conductive filament 52 to provide for continuity therebetween. Contactor 31'', however, has an electrically-conductive spring member 53 to provide both resilient structural mating and electrical continuity.

At the outset, as shown in FIGURES 1 and 2, the device withdraws shorting contact between contactors 31 and turns 2 of helical element 1. Camshaft 5 must be rotated to move contact device 3 to that axial point along helical element 1 where it is desired to make conductive contact. Then, contact device 3 must be braked against further movement, relative to the turns 2, and contactors 31 must be put into contact engagement with the selected turn 2. This is done by causing camshaft 5 to execute a slight rotary motion. This small rotation causes the cam surface 57 of camshaft 5 to push against the inner ends of contactors 31 and move them radially outward into contact with turn 2.

In more detail, the operation is as follows: Drive means 21 impart power via gears 9 and 8 to hub 6. Hub 6 rotates and turns drive rods 4 and actuator shaft 7, together with the hexagonal extension 7'. Hexagonal extension 7' nested in hexagonal hollow 5' causes camshaft 5 to rotate therewith. Contact device 3, slidably mounted on the rods 4 and camshaft 5, and helically mating with the turns 2 of the element 1, is caused to revolve within and along the turns 2. Bearings 13 allow the actuator shaft 7 to turn, with the camshaft 5 and hub 6, on short shaft 14 and allow the bearing block 15 to remain stationary. When the contact device 3 has traversed the turns 2 of the element 1 to a point where it is desired that contact be made, the camshaft 5 is actuated. To accomplish this, braking means 22 are engaged to halt the input drive and to hold the contact device at the desired point. Rotary means 18 are actuated to pivot lever 16 and to withdraw hexagonal extension 7' from camshaft 5. With the pivoting of lever 16, actuator shaft 7 moves longitudinally, withdraws hexagonal extension 7', and turns slightly, as dowel-pin 12 and slot 11 interact. Camshaft 5 turns with actuator shaft 7 and hexagonal extension 7' and, as the contact device 3 is held against rotation by braking means 22, cam surfaces 57 cause contactors 31 to slide outward into contact with the turn 2 of the element 1.

Upon reverse actuation of rotary means 18, spring 10 returns camshaft 5 to its inoperative position. Thus, springs 32 cause contactors 31 to slide inward to interrupt the contact. Rotary means 18 can be mechanically operated by a hand- or foot-lever or any one of several well known arrangements.

FIGURE 3 illustrates a different embodiment of the invention, where the camshaft 5'' has a keyway 62 and a hexagonal hollow 5'. An actuator shaft 63, slidably positioned within hub 6', has a hexagonal extension 7' protruding therefrom which is received in hexagonal hollow 5'. This embodiment has the same dog-leg slot 11 and

dowel-pin 12 arrangement, as in the embodiment of FIG. 1, to crank the camshaft 5'' into operation. However, the camming arrangement and the motive means are different. Actuator shaft 63 is retracted from hub 6' and camshaft 5'' by solenoid 64 and compression spring 65. When drive means 21 are actuated, solenoid 64 is energized and causes actuator shaft 63 to retract to the position I as shown. Snap ring 66 on actuator shaft 63 limits the extent of retraction. Keyway 62 receives a key 37 which is fixed within contact device 3. Key 37 is freely slidable in the keyway 62. Within contact device 3 is cam sleeve 38 which has a transverse slot 67 in which key 37 is secured. Cam sleeve 38 has external cam surfaces 57' and is rotatable within contact device 3. Snap rings 68 in either sides of contact device 3 retain cam sleeve 38 centrally of the contact device 3.

In this embodiment, drive means 21 and solenoid 64 are energized to interrupt shorting contact and to move contact device 3. Drive means 21 rotates gears 9 and 8, hub 6 to which gear 8 is press fit, drive rods 4, and contact device 3. Rotation of device 3 causes cam sleeve 38 to rotate therewith. The key 37 imparts the same rotation to camshaft 5'' as camshaft 5' would be otherwise freely rotatable in hub 6 through the bearing aperture 39. To make contact, drive means 21 are halted and the braking means 22 are energized. Thus gears 9 and 8, rods 4, and contact device 3 are held against rotation. Then, solenoid 64 is de-energized. Biasing means within solenoid 64 overcomes the bias of spring 65 and moves actuator shaft 63 inwardly to position II. This inward movement, through the coacting of dog-leg slot 11 and dowel-pin 12, imparts rotary motion to camshaft 5''. Rotation of the camshaft 5'', coacting with key 37, imparts the same rotation to cam sleeve 38. Rotation of the cam sleeve 38 drives the contactors 31 outward into contact with selected turn 2. By energizing solenoid 64, to impart a reverse rotary motion to camshaft 5'', cam sleeve 38 is returned to its original position. Circular spring 32 urges contactors 31 inwardly withdrawing them from contacting engagement with turn 2.

FIGURE 5 shows the annular groove 59 in the contact device 3 and circular spring 32 resting in recesses 60 of the contactors 31. Key 37 is shown within keyway 62 of camshaft 5''.

FIGURE 6 illustrates another embodiment of the invention where inertial effects are used to make and break contact with the helical element. The drive means 21 are directly joined to the camshaft 40 which in this embodiment is shown by way of example to be a three-sided, generally triangular form in cross-section thus providing three cam surfaces 40a, 40b and 40c.

Wheels 41 mounted on the contact device 3 rotate on turns 2 of the element 1 to cause the device 3 to traverse the length thereof. Upon rotation of the camshaft 40, as is more evident in FIGURES 7 and 8, the contact device 3 lags in complementary motion. This is so because contact device 3 is not positively joined to the camshaft 40 but spaced therefrom as shown by the larger triangular opening 44 and resiliently positioned thereabout by springs 42. Friction and drag of wheels 41 retard movement of contact device 3 until forced by the engagement of camshaft 40 with the walls of opening 44, FIG. 8. This results in an inertial lag of contact device 3. Because of this lag, springs 43 urge contactors 31 inward to break contact with turns 2 of the element 1 prior to movement of device 3. Springs 43 are mounted to pins 69, fixed in an outer surface of contact device 3, and to pins 70 fixed in contactors 31. Slots 71 are provided in the outer surface of the contact device 3 to allow movement of pins 70. Upon cessation of rotary drive from drive means 21, springs 42 cause device 3 to properly orient about camshaft 40. This proper orientation causes the cam surface of camshaft 40 to slide contactors 31 outward and into contact with a helical turn 2 of the element 1.

While I have described the principles of my invention in connection with specific embodiments, it is to be clearly understood that this description is made only by way of example and not as a limitation to the scope of my invention, as set forth in the objects thereof and in the accompanying claims.

I claim:

1. In a device having an element disposed in the form of a helix, a cam shaft, a contact device disposed within said element and about said cam shaft having a contactor adapted to engage by means of said cam shaft said element, means to move said contact device axially of said helix, and means to retract said contactor from engagement with said element during axial movement of said contact device.

2. In a device according to claim 1, wherein said contact device has a plurality of contactors movable radially for contact engagement with said helical element, and said cam shaft includes a plurality of camming surfaces, at least one for every contactor.

3. In a device according to claim 2, wherein said cam shaft extends along the axis of said helix to move said contactors transverse to said axis and within said contact device.

4. In a device according to claim 3, wherein said cam shaft comprises a cam sleeve positioned within said contact device, said sleeve having a cam surface for cooperative engagement with each of said contactors.

5. In a device according to claim 2 wherein said cam shaft is triangular in cross-section and extends along the axis of said helix with its plurality of cam surfaces in cooperative engagement with said plurality of contactors.

6. In a device according to claim 3, further including actuator shaft means having a dog leg for causing rotary displacement of said camshaft to cause said camshaft to move said plurality of contactors radially.

10

15

20

25

30

35

7. In a device according to claim 4, further including actuator shaft means having a dog leg for causing rotary displacement of said cam sleeve to cause said cam sleeve as a result of the displacement to move said contactors radially in a given direction to effect contacting engagement with said helical element, and said actuator shaft means to cause said cam sleeve to cooperate with said retracting means to move said contactors radially in a direction opposite to said given direction to disengage contact with said helical element.

8. In a device, according to claim 5, further including drive means for causing rotary displacement of said camshaft and said contact device to cause said camshaft to move said plurality of contactors radially in a given direction to effect contacting engagement with said helical element, and upon further rotary displacement said camshaft to cooperate with said contact device and retracting means to move said plurality of contactors radially in a direction opposite to said given direction to disengage contact with said helical element.

9. In a device, according to claim 8, wherein said retracting means include means for causing inertial and rotary displacement of said contact device, relative to said camshaft, during movement of said contact device axially of said helix.
